STRIPPER

Arthur L. Leman, Houston, Tex., assignor to The National Supply Company, Pittsburgh, Pa., a corporation of Pennsylvania.

Application January 30, 1936, Serial No. 61,462

2 Claims. (Cl. 288—1)

My invention relates generally to casing heads and more specifically to casing heads having embodied therein a tubing stripper arranged to seal an inner concentric string of tubing in a casing head.

This invention may be conveniently applied to casing heads for use in the oil well art and is more particularly adapted to seal off an inner concentric string of tubing which is suspended 10 from within the casing head from a point thereabove.

A tubing stripper in the casing head art comprises an annular flexible member held in position within the casing head, or similar member, in 15 such a manner as to prevent the passage of fluid therebetween. This annular flexible member depends inwardly and downwardly, contacting the outer surface of the inner string of casing. By reason of its shape the stripper provides an inherent initial pressure against the tubing which 20 aids in effecting a seal therebetween. Again any fluid well pressure acting upon the lower surface of the stripper increases the pressure engagement between the stripper and the tubing, thereby developing a greater sealing engagement 25 in proportion to the existing pressure.

The stripper is purposely made of flexible material to provide for the passage of the tubing therethrough which prevents the escape of the fluid within the well even though couplings of enlarged diameter connecting the sections of tubing 30 must pass through the stripper.

The principal object of this invention is the provision of a flexible stripper that will withstand 35 the repeated passage of enlarged coupling members and the like without endangering the efficiency of the seal thereof. This advantage is gained by the particular design of the stripper member and the manner in which it is incorporated into 40 the casing head structure.

The specific objects of this invention deal with the manner in which the stripper is formed, the manner in which it is locked in place, the manner of forming the annular flexible hinge, the manner 45 of supporting the hinged portion and the mode of backing the hinged portion to give it inherent rigidity without endangering its flexibility.

Other objects and advantages will appear in 50 the following specification.

In the accompanying drawings wherein I have shown a practical embodiment of the principles of my invention,

Fig. 1 is a vertical sectional view of a casing 55 head having the stripper assembled therein.

Fig. 2 is an inverted plan view of the stripper. Fig. 3 is an enlarged sectional view of the stripper showing its contour as a free body.

Fig. 4 is a vertical sectional view of a stripper in sealing engagement with an inner string of 5 tubing with parts of the casing head broken away.

Fig. 5 is a view similar to Fig. 3 showing a tubing coupling of enlarged diameter in sealing engagement with the stripper.

Referring to the drawings and more particularly to Fig. 1, 10 represents a casing head or casing head attachment, arranged to be secured to the well casing, or associated member, as by the threads 11 at the bottom thereof. The casing head member comprises a tubular member having a series of bores arranged to seat or support the several elements necessary to complete the function of the head.

The upper or outer bore 12 is arranged to detachably receive the ring 13 which forms packing 20 seats and chambers for the packing members 14 and 15 which seal the bore 12 and the inner concentric tubing 16.

The ring 13 is provided with the flange 17 having threaded holes in spaced relation and arranged to receive the bolts 18 which when adjusted provide the proper compressive force on the annular gland member 19 for compressing the packing ring 14, thereby sealing the bore 12 of the casing head with the ring 13.

Radially inward of the bolts 18 the upper portion of the ring 13 is provided with a plurality of upwardly extending stud-bolts 20, the positions of which are alternate with respect to the bolts 18. These stud bolts are arranged to receive the inner gland member 21 which compresses the inner packing member 15, forming a seal between the tubing 16 and the ring 13.

It should be noted that the ring 13 provides the packing seats and packing chambers, utilizing the walls of the adjacent members without their being preformed for that specific purpose. Again the ring 13 furnishes the pressure means for both packing members.

The bore 22, which is directly below the bore 45 12 of the casing head, is tapered to receive and hold the slips 23, the function of which is to support the inner concentric tubing 16 in the well known manner.

The next succeeding bores 24 and 25 are for the 50 purpose of supporting and securing the flexible stripper 26 which is preferably made of rubber or the like. The bore 25 is of smaller diameter and ends in the annular pocket or chamber 27 formed by the upturned rim 28, the inner surface 55

of which merges into the bore 29 of the lower portion of the casing head body. The bore 24 is provided with detachable securing means for holding the stripper abutment ring 30.

5 31 represents a casing head vent which opens into the tubular member in the vicinity of the bore 29. This vent is employed to convey the fluid from the well to places where such products may be used or diverted. The lower bore 29 may 10 extend to the lower end of the casing head and the casing securing means, such as the threads 11, may be cut in the face thereof. As shown herein the lower bore 29 is provided with the inner extending portion 32 which acts as a guide 15 for the tubing 16 and also provides reinforcement for the externally threaded section 11.

The casing head member is provided with the elevator lugs 33, one of which is shown at the right in Fig. 1.

20 Referring specifically to the stripper 26, 34 represents the lower annular flange which is arranged to snugly fit in the pocket 27 of the casing head. The upper annular flange 35 fits within the recess 36 of the stripper abutment ring 30.

25 37 represents castellations in the upper surface of the abutment ring 30 which are arranged to receive a tool for turning the ring 30 to compress and hold the stripper in its proper position.

In Fig. 3, the stripper 26 is shown as a free 30 body in full lines, the dotted lines indicate the position it assumes when held in position as shown in Fig. 1. The stripper may or may not be formed in the shape indicated in Fig. 3, but however when assembled the body of the stripper 35 between the annular shoulder 38 and the axis of pivotal movement 39 is compressed by the abutment ring 30. This initial compression will prevent or retard the separation of the shoulder 38 from the adjacent surface of the abutment ring 40 when the skirt of the stripper is flexed downwardly and outwardly. Again, the initial compression of the body and the stripper does not affect the shape or operation of the skirt when the latter is required to perform its function.

45 The upper surface 40 of the stripper between the annular flange 35 and the shoulder 38 is formed as a mating surface to the adjacent wall 40a of the abutment ring. This surface is preferably conical and appears as a tapered surface 50 in the drawings. This particular shape of the surface 40 provides several advantages. It permits the body of the stripper and the abutment ring 30 to be of uniform thickness, thereby providing uniform distribution of compressive and 55 reactive forces. Again it enhances the hinging qualities of the stripper skirt. When the skirt is forced downwardly and outwardly, hinging on the pivot point 39, the conical surface 40 does not have the tendency to abruptly leave its complementary surface of the abutment ring 30. If 60 the casing head is of the multiple type wherein a second string of tubing is vented from above the stripper, any sand or grit will be unable to seek its way between these mating surfaces. 65 This is especially true if an initial compression of the stripper body is employed, as described above, for this section of the stripper must be completely free from compression before it has any tendency to leave its mating surface on the abutment ring.

70 A further important advantage of the surface 40 lies in its capability of retaining the upper portion of the stripper, thereby aiding or relieving the load on the large annular shoulder 35.

The skirt of the stripper is designated gen-

erally by the numeral 41. It comprises a portion of the body section as designated at 42, the annular depending section 43, the sealing contact portion 44, and the flaring nose or rim portion 45.

5 The zone of greatest flexibility is in the section 43 and the effective pivotal point for hinging is at 39. The zone or body section 42 contributes little to the hinging action but if the skirt is flexed to the limit there will be a tendency for the shoulder 38 to move away from the abutment ring 30 unless this portion of the stripper is under initial compression as described above. The section 44 obviously contributes little to the hinging action. This section must be maintained relatively rigid to perform the sealing function. Thus the forces created by the hinging action must be transmitted to this zone to enhance the sealing effect.

46 represents a plurality of web or bracing 20 members which are preferably integral with the stripper and extend from the pivotal point 39 to the tip of the nose portion 45. They may be positioned around the stripper to provide a uniform transmission and distribution of the hinging forces from the section 43 to the section 44. Their number and relative thickness depends upon the size of the stripper and the degree of 25 flexibility required to seal the varying dimensions of the tubular members inserted in the well. 30 To be effective these webs must support part of the zone of greatest flexibility or the section 43. However it should be noted that they are maintained relatively shallow through this section by reason of the fact that the walls of section 43 35 converge to section 44 from whence they are maintained substantially uniform. The deepest sections of these webs occur opposite the tubular sealing zone or section 45 where they become most effective. These webs function to interconnect 40 sections 43 and 44 and are not permitted to contact the bore of the casing head. Their function is confined solely in bracing these two sections.

45 Figs. 3, 4 and 5 illustrate the varying degrees of stressed condition which the stripper undergoes from that of a free body to its application in effecting a seal against the coupler 41. The contour of the outer edge of the web 46 in Fig. 5 is slightly curved owing to the extreme flexure 50 of the stripper as the coupler 41 passes therethrough. In such instances the hinging action is effective along the webs from the point 39, causing the outer edges of the webs to assume a slight arcuate contour.

55 When the well contains fluid under pressure between the casing and the tubing string 16, this pressure is effective against the back of the skirt 41 forcing it into tighter sealing engagement with the tubing 16 and preventing the passage of 60 the fluid therebetween. The fluid pressure is effective against a greater area than that of the contacting sealing surface. This produces a concentrated sealing pressure and by reason of the tapered section 43 and the webs 46, which 65 are effective in substantially an indirect proportion because of their relative position and shape, the skirt is not permitted to collapse in the zone of greatest flexibility and the same sealing section is maintained. A skirt not having these 70 characteristics would collapse under high pressure, causing the rim thereof to curl outwardly, thereby losing the effective sealing contact area, permitting an escape of the fluid until the pressure is released and it is permitted to assume its

normal shape. Under high pressures such a skirt may collapse and regain its normal shape with great rapidity until it has been flexed to such an extent that it fails completely and is torn from its socket.

5 I have thus provided a stripper of relatively light cross section which permits repeated passage of enlarged tubing members without becoming ruptured or permanently deformed and 10 I am enabled to maintain an efficient seal by reason of the force transmitting or bracing webs which prevent collapse of the skirt.

It is evident that the fluid well pressure is 15 effective against the entire perimetral surface of the stripper 26, including the webs 46, and thus a uniform force is effective to produce a sealing engagement for the complete circumference of the tubing member. This is very important.

I claim:—

- 20 1. In a well casing head structure having a tubing string disposed axially therethrough, a flexible tubing stripper for effecting a fluid tight seal between the head and the tubing which comprises an annular base portion arranged to be secured in fluid tight engagement in the bore of the casing head structure, an annular body portion extending radially inwardly and having a bore in spaced relation with the tubing, an an-
- 25

nular skirt portion extending downwardly and inwardly of the body portion and in spaced relation with the bore of the casing head structure, and the tubing, and an annular sealing portion adjacent the lower end of said skirt portion for 5 yieldably engaging the tubing string.

2. In a well casing head structure having a tubing string disposed axially therethrough, a flexible tubing stripper for effecting a fluid tight seal between the head and the tubing which comprises 10 an annular base portion arranged to be secured in fluid tight engagement in the bore of the casing head structure, an annular body portion extending radially inwardly and having a bore in 15 spaced relation with the tubing, an annular skirt portion extending downwardly and inwardly of the body portion and in spaced relation with the bore of the casing head structure and the tubing, an annular sealing portion adjacent the lower 20 end of said skirt portion for yieldably engaging the tubing string, and a plurality of vertically disposed and circumferentially spaced ribs integral with the exterior of said skirt and sealing portions for reenforcing them as they are flexed during the passage of members of enlarged diameter 25 to maintain a fluid under pressure within the casing head structure.

ARTHUR L. LEMAN.
